UNITED STATES PATENT OFFICE.

HUGH D. McKELVEY, OF SALIDA, COLORADO.

MECHANICAL MOVEMENT.

1,324,125.

Specification of Letters Patent.

Patented Dec. 9, 1919.

Application filed December 26, 1918. Serial No. 268,219.

To all whom it may concern:

Be it known that I, HUGH D. McKELVEY, a citizen of the United States, residing at Salida, in the county of Chaffee and State 5 of Colorado, have invented certain new and useful Improvements in Mechanical Movements, of which the following is a specification.

This invention relates to mechanical movements and more particularly to movements of the character shown and described in my application for Patent No. 250,579, filed August 9, 1918.

In this application a construction is disclosed which operates a pump by the combined actions of gravitation and centrifugal force upon a rotating weight, and it is the primary object of the present invention to increase the efficiency of the movement by a 20 novel and more simple arrangement of its coöperative parts.

With this and other objects in view, all of which will fully appear in the course of the following description, my invention 25 consists in the constructions and combinations of elements shown in their preferred form in the accompanying drawings in which like characters of reference designate corresponding parts throughout the several 30 views and in which—

Figure 1 represents a side elevation of a movement containing the improvements;

Fig. 2, a section on the line 2—2, Fig. 1;

Fig. 3, a section taken on the line 3—3,

35 Fig. 2;

Fig. 4, a side elevation of a modified form of the invention;

Fig. 5, a section taken on the line 5—5, Fig. 4, and

40 Fig. 6, a side elevation of another modification of the improved movement.

Referring first to Figs. 1 to 3 of the drawings, the reference numerals 2 designate a pair of standards provided with vertically 45 extending slide-ways 3 in which two boxes 4 have a reciprocating movement.

A shaft 5 rotatably supported in the boxes carries a pulley 6 which by means of a belt 7 is operatively connected with a pulley 8 50 on the rotating element of a motor 9.

The motor is preferably disposed so that its axis of rotation is approximately in a horizontal plane with the axis of the shaft 5 thereby permitting of the reciprocating 55 movement of the boxes without disturbing

the coöperative arrangement of the pulley and the belt, it being understood that the latter has the usual slack to allow for a limited longitudinal expansion.

Springs 10 and 10^a placed in the slide-ways, engage the boxes to cushion their up and downward movements, and set-screws 12 at the upper ends of the standards engage bearing plates 13 for the purpose of regulating the pressure exerted by the upper 65 springs.

The shaft is equipped with two laterally extending spokes or arms 14 which at their outer ends carry weights 15 preferably composed of a number of sections secured between nuts 16.

The shaft extends freely through the head of a rod 17 which connects with a piston 18 slidingly fitted in the stationary cylinder 19 of a double action pump of ordinary construction.

The portion of the shaft upon which the arms are mounted, and the pump may be inclosed in an air-tight cylindrical casing 20 which if so desired can be connected with an exhaust pump for the production of a partial vacuum in its interior to reduce the resistance to the movement of the rotating weights and thereby increase the efficiency of the mechanism.

In order to permit of an up and down movement of the shaft, the casing has in its opposite side walls vertical slots 21 through which the shaft freely extends. The slots are closed against the passage of air by 85 covers 22 which engage the walls of the casing at opposite sides and which have openings in which the shaft is rotatably fitted.

To insure against the leakage of air around the shaft through these openings, 95 the latter are recessed and provided with packings which engage the surface of the shaft as shown in Fig. 2 of the drawings.

In the operation of the mechanism a rotary movement is imparted to the shaft by 100 the action of the motor with which it is connected. During the upward movement of the arms 14 the action of centrifugal force upon the weights at their ends will cause the boxes in which the shafts are 105 supported to move upwardly in their respective slide-ways against the pressure of the springs 10.

During the subsequent downward movement of the arms the centrifugal force aug- 110

mented by the gravitation of the weights, will compel the boxes to move in the opposite direction, and a vertical reciprocating movement is thus imparted to the rotating shaft and the therewith connected piston of the pump.

The plates covering the slots of the casing move with the shaft and by connecting an outlet 23 of the casing with an exhaust pump, a partial vacuum may be produced to reduce the resistance to the movement of the weights and thereby increase the efficiency of the mechanism.

The casing also serves to protect persons in the vicinity of the mechanism against injury by contact with the rotating weights.

By increasing or diminishing the number of sections of which the weights are composed and varying the pressure of the springs 10 by adjustment of the set-screws, the extent of the reciprocating movement of the boxes may be regulated at will.

It will be understood that although the movement has been shown in the drawings in connection with a pump, it may be effectively employed to impart motion to other contrivances which for their operation depend on the impellent movement of a reciprocating element.

In the construction shown in Figs. 4 and 5, the shaft extends freely through the slide-ways of the standards and rests in boxes 24 at the ends of the piston rods 25 of two single-action pumps 26 the cylinders of which are mounted between the diverging legs of the standards.

Springs 10 and 10^a cushion the movement of the boxes in the slide-ways of the standards as in the first described form.

In the construction shown in the drawings, but one weight 28 is provided and it is formed on the rim of a wheel 29 which is connected with a hub on the shaft through the medium of a number of light spokes 30, it being the purpose of the wheel thus formed, to protect operatives and bystanders against injury, in the place of the air-tight casing of the first-described construction.

The modification shown in Fig. 6 of the drawings illustrates the feasibility of producing by rotation of a weighted shaft, a reciprocating motion in planes outside the vertical.

A pair of standards 31 have in this construction circularly bored bearings 34 for correspondingly formed boxes 32 which are secured in their adjusted positions by set-screws 33.

The boxes have diametrical slots 35 which perform the functions of the slide-ways of the standards of the first-described construction, in directing the reciprocating movement of boxes 24 in connection with a piston or pistons of one or more pumps of suitable construction.

If the cylinder of the pump stands vertically as in the construction shown in the drawings, the boxes are formed at the ends of connecting-rods which are pivotally connected with the piston-rods as at 36. The position of the driven element with relation to the movement is, however, arbitrary, and the movement may be employed to actuate reciprocating pistons, tables and other devices which operate in planes outside the perpendicular.

By adjusting the boxes 32 in their respective bearings the movement shown in Fig. 6, may be readily adapted for use in imparting a movement to apparatus of differing types irrespective of their position and construction or the plane in which they operate.

The boxes 24 of the last-described construction support, as before, a rotary shaft 5 which carries one or more weights 15 at a distance from its center of rotation, and springs 10 and 10^a are provided to cushion the reciprocating motion of the boxes.

Having thus explained the mechanical movement in the best forms at present known to me, it will be understood that modifications other than those herein shown and described may be resorted to within the spirit of my invention as defined in the hereunto appended claims.

The number of arms or wheels for the support of the weights may be varied from one to as many as is desirable. Contrivances other than pumps may be placed in operative connection with the shaft as stated hereinabove, and the number of these contrivances that can be operated synchronously by the reciprocation of one and the same shaft is limited only by the capacity of the movement.

In the form shown in Figs. 4 and 5, a hand-crank 37 is provided in the place of the pulley 6 of the construction shown in Fig. 2, to impart a rotary motion to the shaft, it being understood that if a crank is used the operator is obliged to follow the reciprocating movement of the shaft and therefore move the hands which hold the handle of the crank, in a substantially elliptical path.

The driving power of the movement is in each form of my invention, produced by a lateral reciprocating movement created by the actions of centrifugal and gravitational forces upon a weight carried by a rotating shaft at a distance from its center of rotation. The power required to rotate the weighted shaft is inversely proportionate to its velocity and the power produced by its rotation is in direct proportion to the same, and inasmuch as the rotary movement of the shaft is independent of the resistance offered by the load, excepting its frictional contact with the boxes in which it is supported, the energy required for the operation of the

movement at its normal velocity, is little in comparison with the driving power it produces.

Having thus described my invention what I claim and desire to secure by Letters-Patent is:

1. A mechanical movement comprising a rotary element mounted for reciprocation, and a weight carried by the element at a distance from its center of rotation.
2. A mechanical movement comprising a rotary element mounted for reciprocation, a weight carried by the element at a distance from its center of rotation, and means to yieldingly oppose the reciprocating movement of the element.
3. A mechanical movement comprising a rotary element mounted for reciprocation, a weight carried by the element at a distance from its center of rotation, and a driven contrivance having a moving part in operative connection with the element.
4. A mechanical movement comprising a rotary element mounted for reciprocation, a weight carried by the element at a distance from its center of rotation, and an air-tight casing inclosing the path of the weight in its movement with the element.
5. A mechanical movement comprising a rotary shaft, mounted for lateral reciprocation, and a weight connected with the shaft at a distance from its axis of rotation.
6. A mechanical movement comprising a rotary shaft, mounted for lateral reciprocation, a weight connected with the shaft at a distance from its axis of rotation, and a driven contrivance having a moving part in operative connection with the shaft.
7. A mechanical movement comprising a rotary shaft mounted for lateral reciprocation, a weight connected with the shaft at a distance from its axis of rotation, and a pump having a piston-rod in loose connection with the shaft.
8. A mechanical movement comprising a rotary shaft mounted for lateral reciprocation, a weight connected with the shaft at a distance from its axis of rotation, and means to cushion the movement of the shaft.
9. A mechanical movement comprising a rotary shaft mounted for lateral reciprocation, a wheel on the shaft, and an unbalanced weight at the rim of the wheel.
10. A mechanical movement comprising a rotary shaft mounted for lateral reciprocation, a weight connected with the shaft at a distance from its axis of rotation, and a casing providing an air-tight closure for the weight during its movement with the shaft. 55
11. A mechanical movement comprising a supporting structure having vertical slide-ways, a rotary shaft extending in the ways, and a weight carried by the shaft at a distance from its axis of rotation. 60
12. A mechanical movement comprising a supporting structure having vertical slide-ways, boxes movable therein, a rotary shaft supported in the boxes, and a weight carried by the shaft at a distance from its center of rotation. 65
13. A mechanical movement comprising a supporting structure having vertical slide-ways, boxes movable therein, a rotary shaft supported in the boxes, a weight carried by the shaft at a distance from its center of rotation, and a driven contrivance having a moving part in connection with one of said boxes. 70 75
14. A mechanical movement comprising a supporting structure having vertical slide-ways, a rotary shaft having a reciprocating movement in said ways, a weight carried by the shaft at a distance from its center of rotation, and springs cushioning the movement of the shaft. 80 85
15. A mechanical movement comprising a supporting structure, bearings having slide-ways, adjustably supported on the structure to vary the angular position of said slide-ways relative to the perpendicular, a rotary shaft having a reciprocating movement in the slide-ways, and a weight carried by the shaft at a distance from its center of rotation. 90
16. A mechanical movement comprising a supporting structure, rotary bearings thereon, having slide-ways, means for securing the bearings in their adjusted positions, a shaft having a reciprocating movement in the slide-ways, and a weight carried by the shaft at a distance from its center of rotation. 95 100

In testimony whereof I have affixed my signature.

HUGH D. McKELVEY.
